US0D1037549S

(12) **United States Design Patent** (10) **Patent No.:** **US D1,037,549 S**
(45) **Date of Patent:** **** Jul. 30, 2024**

(54) **AEROSOL GENERATOR**

- (71) Applicant: **Nicoventures Trading Limited**, London (GB)
- (72) Inventors: **Robert Whiffen**, Hong Kong (HK); **Davison Dai**, Shenzhen (CN); **Marcus Hartley**, London (GB); **Kang Min Kim**, London (GB); **Jay Lee**, Seoul (KR); **Matthew Tidnam**, London (GB); **Mark Zhang**, Shenzhen (CN)
- (73) Assignee: **NICOVENTURES TRADING LIMITED**, London (GB)

(**) Term: **15 Years**

(21) Appl. No.: **29/835,001**

(22) Filed: **Apr. 15, 2022**

CLAIM

We claim the ornamental design for an aerosol generator, as shown and described.

DESCRIPTION

FIG. 1 is a top front perspective view of an aerosol generator showing the claimed design;

FIG. 2 is a bottom rear perspective view thereof;

FIG. 3 is a top front perspective view thereof;

FIG. 4 is a front view thereof;

FIG. 5 is a rear view thereof;

FIG. 6 is a left view thereof;

FIG. 7 is a right view thereof;

FIG. 8 is a top view thereof; and,

FIG. 9 is a bottom view thereof.

The broken lines in the drawings illustrate portions of the aerosol generator that form no part of the claimed design.
